UNITED STATES PATENT OFFICE

WILLIAM F. RICHARDS, OF MASON, MICHIGAN, ASSIGNOR TO S. M. A. CORPORATION, OF CLEVELAND, A CORPORATION OF OHIO

SPRAY DRIER

Application filed December 7, 1928. Serial No. 324,559.

This invention relates to spray driers for liquid products, such as milk or its components, such as caseinates, milk sugar and the like.

5 The object of the present invention is generally to improve the construction and operation of these driers, and more particularly to provide a system or arrangement of dust collectors which deliver any of the useful fine 10 product which they collect upon the main floor or in a position where it may be collected and mixed and discharged with the main body of the material. It is also an object of the invention to improve the structure of the dust 15 collecting means and the baffling means for the incoming heated air and at the same time avoid undue collection of material upon the baffle and prevent it from becoming scorched or burned and contaminating the rest of the 20 batch.

25 Various features of the invention are clearly set forth in the following description, drawings and claims.

Referring to the drawings, Fig. 1 is a view 30 partly in vertical section and partly in elevation showing the apparatus; Fig. 2 is a vertical section through one of the dust collecting chambers; Fig. 3 is a detail vertical section through an operating cylinder on the line 3—3, Fig. 1; Fig. 4 is a sectional plan view on approximately the line 4—4, Fig. 1; Fig. 5 is a diagrammatic view partly in section and partly in elevation, showing the manner of mounting the parts; and Fig. 6 is a 35 detail view in vertical section showing a construction alternate with that indicated in Fig. 2.

In the drawings 1 represents a suitable floor having a smooth surface with a central 40 opening 2 therein and a substantially radially disposed channel 3 extending beyond the outer wall, as will appear, and in which is a screw conveyor 5 for conveying the material outwardly along the channel to a collecting 45 bin or receptacle (not shown). Arranged upon the floor 1 and concentric with the opening 2 is a cylindrical side wall 6 of what I term the base chamber. Extending inwardly from the upper edge of this wall is an annular dust collector floor 7 connected at its

inner edge to the cylindrical main drying chamber wall 8, which is closed by a suitable ceiling wall 9. The walls 8 and 9 together form an inverted cylindrical casing or container, but the wall 9 which is the ceiling member, is supported independently of the walls 8 as by chains 10 passing over sheaves 10a and having connection with weights 10b, the sheaves 10a being supported on any suitable superstructure such as that indicated at 11, such as a part of the building 11a in which the drier is housed, Fig. 5. Thus, should an explosion occur within the walls 8, the ceiling 9 will yield upwardly to protect the structure from the stresses which would otherwise result; and should the explosion have sufficient force the ceiling 9 may rise above the extremity of the wall 8.

Extending upwardly above the wall 6 is a dust collector side wall 13 having a roof or ceiling 14 extending to the side wall 8 of the main drying chamber. The annular space formed by the wall 13, the floor 7 and the ceiling 14 is divided into a plurality of compartments 15 by suitable radially extending partitions 16. In the floor 7 and grouped around the center of each of these compartments is a collection of openings 17, each provided with a suitable recess 18 for receiving a resilient expansion ring 19 adapted to be inserted within a stocking or other foraminous dust collecting tube or bag 20 to secure its lower end distended. An alternate construction is indicated in Fig. 6 wherein sleeves 19a are secured in the floor 7 with portions extending there above and provided with the prongs 19b indicated as punched out therefrom so that the stockings 20 may be fitted over the upper extremities of the sleeves 19a and there secured by the prongs 19b. The upper ends of these tubes or bags are closed, as at 21, and are connected to a suitable rack or other support 22 carried by the lower end of a rod 23 extending up through the roof 14 and there connected to a suitable vibrating device, such as a piston in the cylinder 24. A spring 26 normally tends to hold each piston upwardly with its stockings or tubes extended, as shown in Fig. 2, but when air is admitted above the piston

it is forced down and the stockings are allowed to sag. By a quick intermittent supply and discharge of air to the cylinder a rapid jar may be given to the stockings to shake the dust collected upon or clinging to their inner surfaces down into the bay of the base chamber which lies outside of the skirt 12, where it falls upon the main floor 1. Any suitable air controlling means (not shown) may be utilized for operating these jarring devices but there is one in connection with each group of stockings.

Each of the chambers 15 is provided with an opening 27 leading to an exhaust header 16 pipe 28 which is connected to any suitable exhausting means.

Lying below the floor 1 is a heating chamber 29 provided with a blower 30, heating coils 31 and an upwardly extending flue 32 which projects up through and snugly fits the opening 2. Rotatably mounted in spiders 33 within this flue 32 is a vertical shaft 34 extending out through the bottom of the flue and there driven by suitable gearing 35 from a motor 36, as by the belt 37, shaft 38 and gearing 39. This shaft 34 projects upward above the upper end of the flue where it is provided with a baffle in the form of a lower cone 39 and an upper cone 40 having their bases connected together and presenting their conical faces one to the incoming air through the flue 32 and the other upward toward the material as it settles down in the process, as will appear. The object of this upper cone is to prevent the fine dust-like product from settling or lodging upon the top of the baffle and becoming scorched or burned and thereby contaminating the entire batch.

Extending radially from opposite sides of the lower cone are arms 41 bent down to form hanger portions 42 extending vertically along the outside of the flue 32 and then bent outward in radial scraper arms 43. The two vertical portions 42 may be strengthened by a suitable connecting ring 44. Secured to the arms 43 are suitable rakes or scrapers generally indicated at 45. The arms 43 and scrapers extend beyond the skirt 12 into the annular bay and are adapted to serve not only that portion of the floor within the main chamber, but also the floor in the bay under the dust collectors, so that all of the material upon the entire floor is scraped up and carried into the channel 3 and is delivered by conveyor 5 outside of the drier.

The material to be treated is supplied through suitable spraying devices 46 spaced around the wall of the main drying chamber near the top thereof. These spraying devices are connected to any suitable source of supply of the material to be treated.

In operation the several parts are set in motion with air delivered to the heating chamber 29 and exhaust effective upon the

exhaust pipes 28. This results in heated air being supplied through the flue 32 and being distributed by the double cone baffle to the main drying chamber where it rises and meets the material to be treated, which is being showered into the chamber by the spraying devices. As the spray or mist settles down through the heated air, it dries and collects upon the main floor, the draft being substantially up at the center and down at the sides to the base of the chamber, where the air stream passes under the skirt 12 into the annular bay. Most of the dried product settles upon floor 1 in the main chamber before the air stream enters the bay, but any fine product which might be carried up and out to exhaust is stopped when the rising air current passes up through the various stockings or tubes and is collected as a fine deposit on the inner surfaces thereof. Periodically the jarring devices for the stockings are operated and any material collected in the stockings shakes down upon the main floor beyond the skirt 12, from whence it is scraped with the material in the main drying chamber and carried into the radial slot and is thence delivered to the outside of the apparatus.

In order to obtain access to the main compartment, the base chamber wall 6 is usually provided with a vestibule 47 leading through a specially formed passageway 48 to the main chamber, the outer opening of this vestibule being closed by a suitable door 49.

Having described my invention, I claim:

1. Drying apparatus of the class described, comprising a hollow casing having wall portions forming a drying chamber, a ceiling member mounted at the top of said chamber and movable bodily and vertically toward and away from the upper edge of said wall portions, and means for yieldingly supporting the ceiling member, whereby upon sufficient increase in pressure within said chamber said ceiling member moves away from the edge of the chamber wall portions and opens a free vent from said chamber to atmosphere.

2. Apparatus for drying liquids, comprising a floor, an inverted hollow casing having a skirt open at the bottom, wall means enclosing an annular bay outside of the skirt, said skirt terminating above the floor level to provide beneath the skirt edge an unobstructed annular entrance to the bay, the floor being continuous throughout the inner casing chamber and the outer bay chamber, floor scraping means rotatable about the central vertical axis and extending through the bay entrance and effective upon substantially the entire floor area, fine dust collecting means adapted to separate the fine dust from the air flowing into the bay and arranged to deliver such material upon the floor of the bay, whereby the scraping means continuously and thoroughly mixes the fine dust de-

- posited upon the bay floor with the coarser material deposited upon the inner chamber floor, to form a homogeneous good quality product, means for spraying liquid to be dried into the upper portion of the inner chamber, and means for supplying a current of heated air to said inner chamber at a level above the lower edge of said skirt and in a direction away from the entrance to said bay,
- 5 to cause the air current to travel through a circuitous path and thereby increase the proportion of material deposited in the inner chamber as compared with that deposited in the bay.
- 10 3. Apparatus for drying liquids, comprising a floor, an inverted hollow casing having a skirt open at the bottom, wall means enclosing an annular bay outside of the skirt, said skirt terminating above the floor level
- 15 to provide beneath the skirt edge an unobstructed annular entrance to the bay, the floor being continuous throughout the inner casing chamber and the outer bay chamber, floor scraping means rotatable about the central vertical axis and extending through the bay entrance and effective upon substantially the entire floor area, fine dust collecting means adapted to separate the fine dust from the air flowing into the bay and arranged to deliver such material upon the floor of the bay, whereby the scraping means continuously and thoroughly mixes the fine dust deposited upon the bay floor with the coarser material deposited upon the inner
- 20 chamber floor, to form a homogeneous good quality product, said bay having an annular roof, and said walls enclosing a series of compartments above said roof and spaced around the outside of said casing, said dust
- 25 collectors being located in said compartments and discharging through the bay roof onto the bay floor.
- 30 4. Drying apparatus of the class described, comprising a casing having wall portions forming a drying chamber, a ceiling member located at the top of said chamber within its wall portion and movable bodily and vertically relative thereto, the upper end of the casing being open and unobstructed to permit the ceiling member to move bodily toward and away from the upper end of the casing, and means for yieldably supporting the ceiling member, whereby upon moderate increase in pressure the ceiling member is adapted to move upwardly within the wall portions and upon heavy increase in pressure to move beyond the wall portions and provide a freely open vent from the chamber to atmosphere.
- 35 45 50 55 60 65 60
- In testimony whereof I hereby affix my signature.

WILLIAM F. RICHARDS.
